UNITED STATES PATENT OFFICE.

BENJAMIN F. FIRMAN, OF JAMESTOWN, NEW YORK, ASSIGNOR OF ONE-HALF TO DANIEL A. MARSH, OF SAME PLACE.

SPLINT-PLANER.

SPECIFICATION forming part of Letters Patent No. 267,990, dated November 21, 1882.

Application filed September 4, 1882. (No model.)

To all whom it may concern:

Be it known that I, BENJAMIN F. FIRMAN, of Jamestown, in the county of Chautauqua and State of New York, have invented certain new and useful Improvements in Splint-Planers; and I do hereby declare that the following is a full, clear, and exact description of the invention, which will enable others skilled in the art to which it appertains to make and use to the same, reference being had to the accompanying drawings, which form a part of this specification.

The object of my invention is to make a simple and efficient machine for planing splints for chairs, &c.; and the improvement will be fully understood by the following specifications and the accompanying drawings, in which—

Figure 1 is a side elevation, and Fig. 2 is a front view.

20 In the drawings, A represents the main body of the frame, which I generally make of wood, on which rests the cast frame B, it being securely fastened to the main frame by bolts. The sides of the cast frame are nearly alike, 25 and are cast in shape to receive the ends of the steel bed-plate H in a groove at their sides, as shown; and they have also grooves in which the movable head C is held, the object of this head being to hold the plane-iron F in position 30 by the clamp E, and the whole head can be raised or lowered at will by the levers d e. This head has eyebolts secured to its under side, and is attached to lever L in such a manner that the head can be brought down to the bed 35 by the weight C being hung on the end of the lever as shown.

a is a set-screw to regulate the cut.

D D are friction-rollers, and are made to revolve by the pulleys P P, the belt on one side 40 being crossed, so as to have them turn in the right direction to draw the splints through.

These rollers are held down by levers and weights, in the usual way.

The practical operation is to raise the planer-head by stepping the foot on the lever and 45 insert one end of the splint under the planer-knife, and far enough back to be taken by the friction-rollers and drawn through the machine. The end is readily caught and returned, so as to plane the end not cut before. As the 50 splints are got out with the grain of the wood, the stationary head for holding the plane is much better than a revolving knife or head, and can be run at much greater speed and the 55 splints all got out of a uniform thickness without changing the machine, and each splint finished without laying it down.

Having described my invention, what I claim as new, and desire to secure by Letters Patent, 60

1. In splint-planing machines, an adjustable head for holding a stationary knife, provided with set-screw and screws for gaging the depth of cut, having foot-levers to raise the head for inserting the splints, in combination with levers 65 and weights for adjusting the pressure and friction-rollers for drawing the splints through, made to operate substantially as shown, and for the purpose set forth.

2. In splint-planing machines, the knife-head 70 C, adjusting-levers d d, and set-screw a, in combination with rollers D D, pulleys P P, weights C C and K, and levers J L, all combined and made to operate in the manner shown, and for the purpose set forth.

In testimony that I claim the foregoing as my own invention I have hereto affixed my signature in presence of two witnesses.

BENJAMIN F. FIRMAN.
